UNITED STATES PATENT OFFICE.

HJALMAR LÖFQUIST, OF STOCKHOLM, SWEDEN.

DRYING-MACHINE.

1,054,853.

Specification of Letters Patent. Patented Mar. 4, 1913.

Application filed May 5, 1911. Serial No. 625,247.

To all whom it may concern:

Be it known that I, HJALMAR LÖFQUIST, subject of the King of Sweden, residing at Birger-Jarlsgatan 21, Stockholm, Sweden, have invented a new and useful Improvement in Drying-Machines, of which the following is a specification.

The present invention relates to improvements in drying machines of the kind provided with electrical water-heating means, its object being to make such machines capable of drying the washed clothes after a slight alteration of the same.

The machine proper is of the type wherein the clothes or other materials are put in a perforated drum which is rotated during the washing process, preferably in alternate directions. Such drum is located in a stationary receptacle or tank containing water which is heated by means of electrical resistance elements mounted in closed metal housings.

According to the present invention the said electrical resistance elements are exchangeable for others provided with perforated housings for use in drying the clothes while same are in the machine and further one of the journals of the washing drum or cylinder is made hollow and connected to a fan for blowing a current of air into the drum during the drying process. The drum is also preferably provided with projections on its internal periphery specially adapted to tumble and displace the clothes during the drying process and so hasten it.

A suitable construction embodying one form of the invention is shown in the accompanying drawings, in which:

Figure 1 is a part sectional side elevation of a washing machine constructed according to the invention and arranged for drying the clothes. Fig. 2 is an end view of same partly in section, and Figs. 3 and 4 are a side view and a section respectively of a detail of the electrical resistance elements arranged for heating the water during the washing process.

In a water receptacle or tank, 1, resting on a frame 2, a perforated drum or cylinder 4 for receiving the clothes is mounted in bearings 3. The receptacle 1 is closed by a plate 5 during the washing as well as during the drying process said plate being preferably semi-cylindrical in order to fit the drum 4. In the plate 5, however, two holes 6 are provided through which turret-like

extensions 7 for the terminals of the heating resistance elements project. The said heating elements consist, in the form shown, of metal wire coils 8, wound on suitable cores 9 suspended on bars 17 and surrounded by metal casings. During the washing, the heating elements shown in Figs. 3 and 4 with completely closed casings 10 are used but during the drying the said heating elements are removed and those shown in Figs. 1 and 2 provided with perforated casings 11 are inserted.

One of the journals 12 of the drum 4 is hollow, as already mentioned, and is connected to the exhaust 13 of a fan 14, which is preferably driven from the same motor 15 that serves to drive the drum. During the washing process the interior of the drum can be shut off from the hollow journal 12 in any suitable manner for preventing water from being thrown out through the latter, the fan being then at rest. During the drying process, however, the fan is rotated and forces a continuous current of dry air into the drum, and at the same time the washed and rinsed clothes in the drum are tumbled continually by the rotation of the drum. The air from the fan 14 enters through the perforations of the drum and is forced to circulate several times through and around the perforated heating elements 11 and again through the drum, whereby an efficient drying is obtained. Of course it would also be possible to lead the air through the heating elements before passing into the drum, but it has been proved, that practically the same results are obtained with the arrangement shown, which also has the advantage of great simplicity. The air saturated with moisture finally escapes through the holes 6.

The drum is as already mentioned, provided with special devices around its internal periphery for tumbling the clothes so as to expose them uniformly to the influence of the air. The said devices consist of longitudinal bars of V-shaped cross-section, made out of a material which is not affected by the washing water, but is capable of receiving an even and smooth surface. A mixture of asbestos and cement has proved to be especially suitable for forming these bars, and said bars may therefore be formed from plates of such material, which is preferably polished.

Having now particularly described the

nature of my invention and the manner of its operation, what I claim is:—

- 5 1. A drying machine for clothes comprising a perforated drum for receiving the clothes, means for transmitting a reciprocating rotary motion to said drum, a receptacle surrounding said drum and electrical heating means with perforated casings mounted in said receptacle.
- 10 2. A drying machine for clothes comprising a perforated drum for receiving the clothes, means for transmitting a reciprocating rotary motion to said drum, a recep-

tacle surrounding said drum, electrical heating means with perforated casings mounted 15 in said receptacle, a hollow journal supporting said drum and communicating with the interior thereof, and a fan discharging into said hollow journal.

In testimony whereof I have signed my 20 name to this specification in the presence of two subscribing witnesses.

HJALMAR LÖFQUIST.
